UNITED STATES PATENT OFFICE.

FREDERICK V. HAGAN, OF SAN FRANCISCO, CALIFORNIA, ASSIGNOR OF ONE-THIRD TO
WELLER ROBINSON, OF NAMPA, IDAHO.

MEANS FOR DESTROYING VESSELS.

1,201,176.

Specification of Letters Patent.

Patented Oct. 10, 1916.

Application filed November 13, 1915. Serial No. 61,803.

To all whom it may concern:

Be it known that I, FREDERICK V. HAGAN, a citizen of the United States, residing at San Francisco, in the county of San Francisco and State of California, have invented new and useful Improvements in Means for Destroying Vessels, of which the following is a specification.

This invention relates to means for destroying marine vessels and it consists in the novel features hereinafter described and claimed.

An object of the invention is to provide means of the character indicated especially adapted to be carried by a sub-marine vessel and which includes magnets when energized by an electric current adapted to attach themselves to the hull of the vessel about to be destroyed. The magnets are energized from current the source of supply of which is carried by the sub-marine and which is transmitted to the magnets by wires which may play out from the sub-marine vessel as it retreats under water from the prey. A mine is carried by the structure which includes the magnet and may be shot off at a desired time thus effecting the destruction of the vessel. The mine may be exploded by a current from the sub-marine or it may be exploded by a clock work mechanism provided in the mine structure.

In the accompanying drawings:—Figure 1 is a schematic view showing the manner of applying the destroying means to a floating vessel. Fig. 2 is a side elevation of the sub-marine vessel with parts in section.

As illustrated in the accompanying drawing, the means for destroying a floating marine vessel, comprises a sub-marine vessel 1 of any suitable design or pattern. The vessel 1 is provided in its bottom with suitable storage batteries 2 and above the batteries with suitable oxygen tanks 3. The tanks 3 are designed to contain oxygen gas or any other chemical for supplying air to the operators of the submarine vessel. The storage batteries 2 are designed to supply the electric current to the magnets, hereinafter described, and also to the mine when an electric current is used for exploding the mine.

Frames 4 are mounted upon the top of the submarine vessel 1 and frames 5 are normally carried by the frames 4. Magnets 6

are mounted at the corner portions of the frames 5 and wires 7 are connected with the said magnets and are wound upon coils 8 mounted upon the submarine vessel 1. From the coils 8 the wires 7 are connected with the batteries 2 in any suitable manner. A mine 9 is carried by each frame 5 and the said mine may be connected by means of wires with the batteries 2 or the mines may be provided with clock works adapted to operate mechanisms for exploding the same.

In operation the submarine vessel is submerged below the surface of the water and approaches the prey. When the submarine vessel arrives at the hull of the floating vessel about to be destroyed, the current from the batteries 2 is turned on the wires 7 whereby the magnets 6 are energized and by attraction they will cling to the sides of the vessel about to be destroyed. The submarine vessel 1 then withdraws or retreats to a safe distance and in the event that an electric current is used for exploding the mine 9, the said current is turned on and when it explodes the hull of the floating vessel is blown in and the said vessel in consequence thereof sinks or is destroyed.

In the event that the clock work mechanism is employed for exploding the mine 9, the submarine vessel 1 withdraws to a safe distance from the prey and at the designated time or interval the clock work mechanism operates the exploding means whereby the mine is set off.

From the above description taken in conjunction with the accompanying drawing, it will be seen that very simple and cheap means are provided for effectively accomplishing the destruction of a floating marine vessel and that the same may be accomplished in a manner which assures the safety of the operators of the submarine vessel during the application of the destroying means at the time that the explosion thereof takes place.

Having described the invention what is claimed is:—

Means for destroying a floating vessel comprising a submarine vessel having a compartment located at its top, a frame inclosed in the compartment and removable therefrom; magnets mounted upon the

frame, electric means carried by the submarine vessel for exciting the magnets to cause them to remove the frame from the compartment and to adhere to the floating vessel, a mine carried by the frame, and means for exploding the mine by the electric means carried by the submarine vessel.

In testimony whereof I affix my signature in presence of two witnesses.

FREDERICK V. HAGAN.
